MANUFACTURE OF SUBSTITUTED MALONIC
ACID ESTERS

Thomas S. Carswell, Kirkwood, and Harry W. Faust, St. Louis, Mo., assignors, by mesne assignments, to Monsanto Chemical Company, a corporation of Delaware

No Drawing. Application March 14, 1932,
Serial No. 598,872

7 Claims. (Cl. 260—106)

This invention relates to the manufacture of alkyl and aralkyl derivatives of malonic acid esters, and it has particular application to the manufacture of mono and di-alkyl or aralkyl C-substituted derivatives of esters of malonic acid.

The mono and di-alkyl C-substituted derivatives of malonic acid ester are intermediates in the manufacture of barbituric acid derivatives.

Heretofore, it has been the practice to manufacture the di-alkyl C-substituted malonic acid esters by reacting malonic acid ester with a mol. equivalent of sodium ethylate according to the following reaction:

and thereafter displace the sodium with an alkyl group by means of an alkyl halide according to the following reaction:

The resulting mono-alkyl derivative is then reacted with a second mol. equivalent of sodium ethylate and the combined sodium is then replaced with an alkyl group by means of its corresponding halide.

Although it has been proposed to proceed from one alkylation to the next without isolating the mono-alkyl product, in practice it is preferable because of the improved yields thereby made possible to isolate the intermediate product from the impurities and by-products. Even then, however, the overall yield by the two-stage process seldom exceeds 70% of theory.

We have found that by reacting the alkyl halide with the malonic acid ester in the presence of an alkali-alcoholate, while avoiding a substantial excess of the alkali metal derivative of the malonic acid ester, one can proceed directly to the di-substituted derivative without isolating the intermediate products. The yields thus obtainable are materially greater than those otherwise obtainable and the processing operations and costs are at the same time reduced.

The principal object of the present invention is to provide a method of effecting the alkyl or aralkyl substitution directly, and with improved yields as compared to those attainable by present day methods.

The invention likewise contemplates eliminat-

ing several steps of the process now commonly employed.

A further object of the invention is to provide a process by which it is possible to reduce to a minimum the destructive effect of the alkali on the malonic acid ester which effect we have found contributes very greatly to the comparatively low yield of product. These together with other objects will be more apparent from the description of an embodiment of the process hereinafter set forth.

To manufacture the C-di-ethyl malonic acid ester, which may be represented structurally:

(where R_1 and R_2 represent the ethyl groups) 20
a malonic acid ester such as di-ethyl ester of malonic acid is charged into an autoclave provided with an agitating mechanism and a jacket for regulating the temperature of the contents of the autoclave. A mol equivalent of ethyl chloride is introduced preferably after displacing 25 the air present in the autoclave as by evacuation. The temperature is then adjusted to approximately 50°-60° C. after which a mol equivalent of sodium ethylate dissolved in ethyl alcohol is added slowly over a period of two hours 30 while maintaining a temperature of 50°-60° C. 35 and while agitating the reaction mixture. The sodium derivative thus produced reacts under the prevailing conditions with the ethylating agent. The sodium ethylate reagent is prepared conveniently by dissolving approximately 80 parts by weight of metallic sodium in 875 parts by weight of absolute ethyl alcohol. Subsequently, the temperature of the reaction mixture is raised to approximately 90° C. and the reaction 40 is allowed to proceed for approximately two hours. At the end of this period, the mono-ethyl substitution is essentially complete.

To prepare the di-ethyl derivative, the temperature of the reaction mixture is again adjusted to approximately 50°-60° C. and a mol equivalent of ethyl chloride is introduced, after which a mol equivalent of sodium ethylate dissolved in ethyl alcohol is introduced over a period of two hours as in the preceding stage. At the end of the two hour period, the temperature is raised again to approximately 90° C. and maintained for approximately two hours. A 90% yield of the di-ethylated malonic acid ester is obtained, which is separated and purified in the usual manner.

If one desires to prepare the ethyl butyl derivative in lieu of the di-ethyl derivative, butyl chloride is introduced at the end of the first stage in lieu of ethyl chloride. For this purpose, one may also substitute sodium butylate dissolved in butyl alcohol for the sodium ethylate reagent as well as remove the ethyl alcohol introduced in the first stage and substitute a butyl alcohol corresponding to the alkylating agent to be employed in the second stage.

The corresponding benzylated malonic acid ester is prepared by a method analogous to that described above. Similarly, one may prepare the ethyl benzyl derivative by substituting benzyl chloride for the ethyl chloride which is employed in the second stage of the reaction.

It is to be noted that the temperatures specifically set forth may be varied. In general, it is preferable to increase the temperature during the later stages of each alkylation. If desired, however, the temperature may be increased gradually during the reaction cycle, although in general we prefer to introduce all of the alcoholate before raising the temperature. It is likewise to be noted that the foregoing examples provide for a two stage ethylation in the preparation of the C-di-ethyl malonic ester. This precise cycle of operation is not essential, but is rather a matter of convenience, since the mono ethyl product obtained after the first stage may be employed in the preparation of products other than the C-di-ethyl ester. In case a di-alkyl derivative is desired, such for example, as the di-ethyl derivative, one may add the two mol equivalents of the ethyl chloride at the outset and thereafter add the alcoholate progressively during the course of the reaction.

Obviously, the temperature conditions may be varied and the time of reaction may be varied as is well understood by those skilled in the art. Similarly, the concentration of the alcoholate in the alcohol solvent may be varied.

If desired, the alkylating agent may be introduced simultaneously with the alcoholate. Or, when the di-alkyl derivative is desired, two mol equivalents of the alkylating agent may be introduced at the outset. We have likewise observed that one may react the malonic acid ester with a portion of the alcoholate preliminary to the introduction of the alkylating agent. In general, it is desirable to avoid the presence of a substantial proportion of the alkali metal derivative of the malonic acid ester, such as prevails under the conditions of the present day processes wherein the mono-alkali metal derivative of malonic acid ester is formed preliminary to the introduction of the alkylating agent.

In lieu of ethyl chloride, one may employ other alkylating agents, such as the bromide, di-ethyl sulfate, di-ethyl sulfite, etc. Other alkyl derivatives may be produced in an analogous manner by appropriate substitution of the corresponding alkylating agents. Thus for example, methyl, propyl, butyl halides may be employed in the preparation of the corresponding derivative of the malonic acid ester. Similarly, an aralkylating agent, such as benzyl chloride or bromobenzyl chloride, may be employed whereby the corresponding aralkyl derivatives of the ester are pro-

duced. Alcoholates other than the sodium ethylate which may be employed include: potassium ethylate, sodium methylate, sodium butylate, etc.

The term "malonic acid ester" is generally understood in the art to mean the di-ethyl ester of malonic acid. However, as used herein it is not so limited, but is intended to cover other esters including for example di-methyl or di-butyl ester of malonic acid.

From the foregoing description, it will be apparent that we have provided a method for manufacturing mono and di-substituted malonic acid esters whereby the intermediate steps now commonly employed are eliminated, with improvement in yield of the desired product. It will likewise be apparent that although one specific embodiment has been set forth and certain modifications have been indicated, the invention is not so limited, but contemplates broadly the interaction of a malonic acid ester with an alkylating or aralkylating agent in the presence of an alkali metal alcoholate while avoiding the presence of a substantial quantity of unreacted alkali metal substituted malonic acid ester.

What we claim is:

1. The method which consists in causing a malonic acid ester to react with a material selected from a group consisting of an alkylating agent and an aralkylating agent, while adding progressively during the course of the reaction an alkali metal alcoholate.

2. The method which consists in causing the di-ethyl ester of malonic acid to react with an alkylating agent while adding progressively during the course of the reaction an alkali metal alcoholate.

3. The method as defined in claim 2 and further characterized in that the alcoholate is sodium ethylate.

4. The method which consists in reacting the di-ethyl ester of malonic acid with a mol equivalent of an ethylating agent while adding during the course of the reaction substantially one mol of sodium ethylate and avoiding the presence of a substantial unreacted excess of the sodium ethylate.

5. The method as defined in claim 4 and further characterized in that the resulting reaction product is caused to react with a second mol equivalent of ethylating agent while adding during the course of the reaction a second mol equivalent of sodium ethylate and avoiding the presence of a substantial unreacted excess of the sodium ethylate.

6. The method which consists in causing a malonic acid ester to react with a material selected from the group consisting of an alkylating agent and an aralkylating agent, which method is characterized in that an alkali metal alcoholate is added progressively during the course of the reaction while avoiding the presence of a substantial quantity of the alkali metal alcoholate in the reacting mixture.

7. The method as defined in claim 6 and further characterized in that the alkali metal alcoholate reagent is dissolved in the corresponding alcohol.
